UNITED STATES PATENT OFFICE.

HENRY H. BAKER, JR., OF BUFFALO, NEW YORK, ASSIGNOR OF ONE-HALF
TO HARVEY D. BLAKESLEE, OF SAME PLACE.

NECKTIE-FASTENER.

SPECIFICATION forming part of Letters Patent No. 439,371, dated October 28, 1890.

Application filed February 15, 1890. Serial No. 340,506. (No model.)

To all whom it may concern:

Be it known that I, HENRY H. BAKER, Jr., a citizen of the United States, residing at the city of Buffalo, in the county of Erie and State 5 of New York, have invented a new and useful Improvement in Necktie-Fasteners, of which the following is a specification.

This invention relates to the retaining devices which are more especially employed on 10 neckties having a band encircling the collar, and which prevent the tie from shifting out of place.

The object of my invention is to produce a 15 cheap fastener of this character which is conveniently engaged with the collar or front collar-button, and which may be readily detached from a worn tie and applied to a new one, if desired.

In the accompanying drawings, Figure 1 is 20 a front elevation of a necktie provided with my improved fastener, the latter being shown by dotted lines. Fig. 2 is a rear or inside view of the tie, showing the fastener in elevation. Fig. 3 is a side elevation of the fastener. Fig. 25 4 is a perspective view of a modified construction of the fastener; and Fig. 5 a side elevation thereof, showing the same engaged with the button-hole of the collar.

Like letters of reference refer to like parts 30 in the several figures.

My improved fastener consists of an upright stem or shank A, which is provided at its lower end with a pin or clasp b, whereby the fastener is attached to the back of the 35 necktie and at its upper end with a fork or bifurcated portion c, which engages under the front collar-button d, (shown by dotted lines in Fig. 1,) and embraces with its jaws the neck or shank of the button. As shown in the 40 drawings, the fork opens upwardly, and its bight or lower closed portion, bearing against the under side of the collar-button, prevents upward displacement of the tie, while the jaws of the fork, bearing against opposite sides of 45 the button, prevent the tie from shifting sideways. The fastener is attached to the tie at such an elevation that the fork is located at

the upper end of the tie, but does not project above the same.

The upper ends of the fork c are preferably bent or curved outwardly, as shown in Fig. 3, to facilitate engaging the fork under the collar-button and prevent the ends of the fork from entering the button-hole of the collar. The stem or shank A is also preferably 50 curved slightly and arranged with its convex side against the person. This construction brings the lower portion of the shank forwardly some distance and permits the fastener to be moved inward sufficiently to enable its fork to be conveniently guided under the collar-button. The fork is readily passed under the button in the act of drawing up the tie into place by its band.

By providing the fastener with a pin or 55 clasp b it is securely attached to the tie and not liable to become lost, and it is at the same time rendered detachable, so that it may be readily transferred from one tie to another, if desired.

In the modified construction represented 60 by Figs. 4 and 5 the fork at the upper end of the fastener is arranged in a position at right angles to that occupied by the fork of the first-described construction, and instead of 65 engaging under the collar-button it enters the button-hole of the collar so as to bear with its bight or closed lower portion against the upper side and ends of the button-hole, and thus hold the necktie against displacement.

The fastener is bent from a single piece of 70 wire doubled and shaped at its center to form the fork and having its branches twisted together to form the stem, the ends of the 75 branches terminating, respectively, in a hook or keeper and a pin, as shown, and constituting the clasp. By this construction no solder or separate parts are required, and the fastener can therefore be produced at very small 80 cost. By this construction the stem and fork are formed of a double thickness of wire, rendering the same very stiff and not liable 85 to be bent, and the use of solder or separate

parts is avoided, thus enabling the fastener to be produced at very small cost.

I claim—

5 A necktie-fastener consisting of a single piece of doubled wire twisted together to form a stem or shank and having its upper doubled portion bent to form a rigid fork opening upwardly in line with the stem, and its lower

portions bent to form the pin and keeper of a clasp, substantially as set forth.

Witness my hand this 11th day of February, 1890.

HENRY H. BAKER, JR.
